UNITED STATES PATENT OFFICE.

MAURICE D. MICKLIN, OF OMAHA, NEBRASKA.

EXTENSIBLE GRILLE.

Application filed April 16, 1928. Serial No. 270,314.

This invention relates to an extensible grille, and has for its object to provide a metallic grille of such construction that it may be readily applied to fill a part of the area 5 between upright supports as a guard or barrier, and may be used to advantage upon screen doors or upon the frames of window screens.

It is well known that, on account of their exposed position, the screens upon screen doors 10 often become injured and detached or loosened from the frames. The grille to be described herein may be conveniently applied to screen doors of various widths and will adequately resist all stresses directed thereto and 15 will prevent injury to the screen.

The new and useful features of the invention are fully described herein and illustrated 20 in the accompanying drawing, it being understood that changes may be made in form, size, proportion of parts and minor details, 25 said changes being within the scope of the invention as claimed.

In the drawing Fig. 1 is a view in side elevation of a part of a screen door and door frame, with the grille applied thereto. Fig. 25 2 is a side view of an extensible supporting-strip. Fig. 3 is a view, partly in section, showing a part of one of the tubular, telescoping grille-supports.

Referring now to the drawing for a more particular description, the invention is shown and described in connection with a screen door frame 4 hinged to a door casing 5, and 30 consists, in part, of a rectangular frame including a pair of side strips 6 which are secured at their ends to an upper extensible support 7, and to a lower extensible support 8.

Each support 7 and 8 consists of a metallic tube or sleeve 9 provided at its ends with secondary sleeves or tubes 10 adapted to have 35 sliding movements in a tube 9 and each provided with a foot-piece 11 adapted to be secured to the frame of the screen door.

Numeral 12 indicates a plurality of upright parallel metallic strands uniformly spaced apart each being mounted at its ends upon the tubes 9, said mountings being by means 40 of terminal loops 13, the ends of the strands being bent to form said loops 15.

Numerals 16 and 17 respectively indicate 45 pairs of opposed supporting-strips, each being provided with a foot-piece 18 for a mount-

ing upon the frame of the screen door as 55 shown in the drawings. However wire may be used if desired. They are interwoven, that is to say the opposed sides of the strands 12 are engaged in alternation by the strands 14. Also the opposed sides of the support- 60 strips 16 and 17 are engaged in alternation by the vertical strips 12.

As thus described it will be seen that the grille may be readily mounted upon the door frames of various widths. The secondary or 65 inner tubes 10 may be drawn outwardly from the tubes 9, the pairs of supporting-strips 16 and 17 being also drawn outwardly from the grille so that the foot-pieces 11 and 18 will engage the door frame 4 and may be secured 70 thereto, the function discharged by the horizontal strips 16 and 17 being to support the web or grille between its top and bottom.

It will be appreciated that the device consists of few and simple parts and therefore 75 may be manufactured economically. Also on account of the construction as described the grille will be adequately supported and bending or buckling of the strands, which might be caused by shocks or undue pressure, will be 80 adequately resisted.

I claim as my invention:—

1. A grille for door and window frames, comprising an open mesh panel portion, spaced apart supports on the panel portion 85 for attachment to a frame, and independent reinforcing strips for attachment at one end to the frame and adapted for intermeshing engagement at their other ends in said panel portion to steady the same between said supports.

2. A grille for door and window frames, comprising spaced apart supporting bars, spaced apart side strips attached to said bars and forming therewith a substantially rectangular frame, interwoven spaced apart strands of wire secured to said bars and to said side strips thereby forming an open mesh panel, said supporting bars extending beyond the side strips for attachment to a frame, and separate and independent reinforcing strips between said bars adapted to be secured at one end to the frame and to threadingly engage the mesh panel at their other ends thereby reinforcing and stabilizing the panel.

In testimony whereof, I have affixed my signature.

MAURICE D. MICKLIN.
